BREATHER PIPE CAP

Application filed December 14, 1931. Serial No. 580,994.

This invention comprehends the provision of a breather pipe cap of novel construction, which enables the compression within the crank case of the engine to more readily escape, and thus prevent the oil from being forced back through the cylinders with resultant waste.

It is also the object of the invention to provide a breather pipe cap by means of which any oil passing from the pipe with the fumes, will be separated therefrom and returned to the crank case, while the fumes are exhausted to the atmosphere.

In carrying out the invention, we provide a breather pipe cap constructed to prevent dirt, dust or other foreign matter from entering the crank case through the pipe, and one which can be quickly and conveniently removed from the pipe as the occasion may require.

Other objects and advantages will appear when the following detail description is read in connection with the accompanying drawing, the invention residing in the construction, combination and arrangement of parts as claimed.

In the drawing forming part of this application like numerals of reference indicate similar parts in the several views and where-

in:

Figure 1 is a fragmentary view of an internal combustion engine illustrating the invention.

Figure 2 is a vertical sectional view through the breather pipe cap.

Figure 3 is a sectional view on line 3-3 of Figure 2.

Referring to the drawing in detail 10 indicates an internal combustion engine provided with the usual breather pipe 11.

The present invention provides a cap for the breather pipe constructed to prevent waste of lubricant oil as well as to increase the smoothness and efficiency of the operation of the engine. The cap in its entirety may of course be constructed from any suitable material, and also vary in size and cross sectional contour without departing from the inventive idea.

The cap includes a body portion 12 prefer-

ably of cylindrical contour, and is closed at its top and bottom as indicated at 13 and 14 respectively. The body portion is of a size to afford the breathing pipe maximum air space, with a view of enabling the compression within the crank case of the engine to more readily escape, and also receives the oil which passes from the breather pipe with the fumes and returns the oil to the crank case for further use. In carrying these ideas into effect we divide the body portion 12 into a relatively large compartment 15 and a relatively smaller compartment 16, by means of a partition 17. This partition depends from the top 13 of the body portion 12, and terminates in spaced relation to the bottom 14, thereby establishing communication between the respective compartments at a point beneath the partition 17.

Located centrally within the body portion 12 is a hollow tubular member 18 which is substantially coextensive in length with the body portion 12, but terminates in spaced relation to the top 13 thereof. This tubular member 18 receives the exhaust from the breather pipe 11, and conveys the same into the compartment 15 of the cap, inasmuch as the tubular member 18 is located in this compartment and spaced from the partition 17 as illustrated. Consequently the fumes, and whatever oil is delivered into the cap 12 are caused to pass downwardly through the compartment 15 to the bottom thereof, and the oil is returned to the crank case through the breather pipe, while the fumes pass upwardly through the compartment 16 into an exhaust pipe 19 leading from the cap adjacent the top thereof. A flexible pipe 20 has one end connected with the exhaust pipe 19 to convey the fumes to the atmosphere, and this flexible pipe 20 can be of any desired length and terminate at any particular location about the car, so as to prevent the fumes from entering the latter.

While the cap may be associated with the breather pipe 11 in any suitable manner, we preferably project the tubular member 18 beneath the bottom 14 of the cap, and this portion of the tubular member is adapted to be frictionally fitted within the breather pipe

11 as illustrated in Figure 1. The projecting portion of the pipe is also provided with an annular bead 21 which reposes upon the upper end of the pipe 11 and thus limits the insertion of the tubular member within the latter.

By virtue of the invention hereinabove described it will be manifest that the compression within the crank case of the engine is allowed to more readily escape through the breather pipe into the cap 12, the fumes and oil carried thereby passing through the tubular member 18. The fumes strike the top 13 of the cap and are directed thereby downwardly into the bottom of the cap, the fumes passing beneath the partition 17, and thence upwardly through the compartment 16 to the exhaust pipe 19. Consequently the compression within the crank case is prohibited from forcing the oil back through the cylinders with resultant waste, and by releasing the compression of the crank case in the manner stated, the smoothness and efficiency of motor is enhanced. While the fumes are carried away through the flexible pipe 20, the oil which separates itself from the fumes within the cap 12 is returned to the crank case for further use, this being accomplished by providing the tubular member 18 with an oil return opening 22 located immediately adjacent the bottom 14 of the cap. The entire device can be quickly and conveniently associated with or removed from the breather pipe 11 as the occasion may require.

While it is believed that from the foregoing description the nature and advantages of the invention will be readily apparent we desire to have it understood that we do not limit ourselves to what is herein illustrated or described and that such changes may be resorted to as fall within the scope of what is claimed.

What is claimed is:

1. A breather pipe cap comprising a vertical body portion closed at the top and bottom, and open-ended tubular member extending into the body portion through its bottom and spaced from the top thereof, said tubular member being adapted for connection with the breather pipe to convey the exhaust therefrom into said body portion, said tubular member having a transverse oil return opening therethrough within and adjacent the bottom of the body portion, and a lateral outlet pipe projecting from the body portion adjacent its upper end.

2. A breather pipe cap comprising a vertical body portion closed at the top and bottom, a partition depending from the top of the body and terminating in spaced relation to the bottom thereof, said partition dividing the body into two compartments, an open-ended tubular member extending through the bottom of said body portion into one of said compartments and terminating in spaced

relation to and adjacent the top of said body portion, said tubular member being adapted for connection with the breather pipe to convey the exhaust therefrom into said one compartment, said tubular member having a transverse oil return opening therethrough within and adjacent the bottom of said body portion, and a lateral outlet pipe leading from the other of said compartments adjacent the upper end of the body portion.

3. A breather pipe cap comprising a vertical body portion closed at the top and bottom, an open-ended tubular member extending into the body portion through its bottom and spaced from the top thereof, said tubular member being adapted for connection with the breather pipe to convey the exhaust therefrom into said body portion, said tubular member having a transverse oil return opening therethrough within and adjacent the bottom of the body portion, and a lateral outlet pipe projecting from the body portion adjacent its upper end, said tubular member having a projecting lower end adapted to be positioned in the breather pipe and provided with an annular bead adapted to repose on said breather pipe.

In testimony whereof we affix our signatures.
